UNITED STATES PATENT OFFICE.

JOHN F. BLACKMAN, OF BROOKLYN, ASSIGNOR TO VANDERBURG, WELLS & CO., OF NEW YORK, N. Y.

DESIGN FOR WOOD TYPE.

Specification forming part of Design No. 6,342, dated January 21, 1873.

To all whom it may concern:

Be it known that I, JOHN F. BLACKMAN, (assignor to VANDERBURG, WELLS & Co.,) of Brooklyn, Kings county, New York, have originated and produced a new and original Design for Wood Type, of which the following is a specification:

The nature of my design is fully shown in the accompanying typographic impression, to which reference is made.

What I claim as new is—

The design for wood type, as herein shown.
JOHN F. BLACKMAN.

In presence of—

A. SIDNEY DOANE,
Wm. HASTINGS.
